UNITED STATES PATENT OFFICE.

ENOCH P. STEVENS, OF CHICAGO, ILLINOIS.

KILN.

1,111,871.

Specification of Letters Patent. Patented Sept. 29, 1914.

Application filed November 21, 1912. Serial No. 732,627.

To all whom it may concern:

Be it known that I, ENOCH P. STEVENS, a citizen of the United States, residing at Chicago, in the county of Cook and State of Illinois, have invented certain new and useful Improvements in Kilns, of which the following is a specification.

My invention relates to kilns, and refers particularly to kilns used for burning bricks, tiles, and other similar ceramic material.

It is one of the objects of my invention to provide a kiln in which there shall be an even distribution of heat throughout the entire interior of the kiln so that the material within the kiln may be uniformly heated.

A further object of my invention consists in providing a great radiation surface so that the fuel may be utilized to the greatest extent.

A still further object of my invention consists in so conducting the combustion that a complete oxidation of the fuel occurs whereby the amount of fuel which is used may be considerably reduced from the amount heretofore employed in similar operations.

The various advantages of my invention will be more readily understood by reference to the accompanying drawings, which show a preferred embodiment of my improvements, and in which:

Figure 1 is a vertical section through my improved kiln; Fig. 2 is an enlarged horizontal section taken on the line 2—2 of Fig. 1; Fig. 3 is a fragmentary enlarged vertical section showing a portion of the fire box and the flues connected therewith; and Fig. 4 is an enlarged fragmentary vertical section taken on the line 4—4 of Fig. 1.

My improved kiln is preferably rectangular in shape, and rests on the foundation 10, of concrete, or other suitable material. On each side of the kiln is located a series of fire boxes 11 having the grates 12. Each of these fire boxes is provided with a fire door 13 in the usual manner. From each of the fire boxes 11 a plurality of flues 14 extend upwardly just inside of the side walls 15 of the kiln. Each of the flues 14 continues into a roof flue 16 within the roof 17, and then communicates in turn with the central flue 18, the lower end of which is connected with the floor flue 19. Extending parallel with the floor flues 19 and alternating therewith are the floor flues 20, which communicate with flues 19 through the passages 21. Each

of the flues 20 communicates with a central chimney flue 22.

As clearly shown in Figs. 1 and 2, my kiln is built with two chambers 23 and 24, the flues of each of these chambers being similar to each other. The corresponding flues 20 of each chamber preferably communicate with a single central chimney flue 22, but, if desired, this chimney flue may be provided with a vertical partition so that the two chambers of the kiln may be operated entirely independently of each other.

As clearly shown in Fig. 2, the hollow tiles forming the flues 19 are slightly separated from the hollow tiles forming the flues 20, so that radiation surfaces are obtained on three of the four sides of each tile.

As clearly shown in Figs. 1 and 4, the tiles of the roof flues 16 project beyond the intermediate bricks 33, thereby affording excellent radiation from the surfaces of the roof tiles, while the tiles of the flues 18 similarly project beyond the surfaces of the brickwork of the chimney flues 22.

As best shown in Figs. 1 and 3, a passage 34 communicates with the exterior, and leads to each of the passages 21 between the floor flues 19 and 20. By means of these passages 34 it will be evident that additional air is mixed with the gases passing from the flues 19 to the flues 20, and perfect combustion is thereby assured. The end walls 25 of the kiln are provided with fire boxes 26, access to which is obtained through the fire doors 27. The flues 28 lead upwardly from the fire boxes 26 and communicate with the flue 29, which, in turn, communicates with a suitable stack, not shown in the drawings.

Having thus described the construction of my improved kiln, its operation may now be readily understood: The fire boxes 11 being provided with fuel, the gases pass upwardly through the flues 14 into the flues 16, and then down through the flues 18. From the latter the gases pass into the floor flues 19 into the connecting passages 21. At this point air is introduced through the passages 34, and combustion is thereby further promoted and the gases continue through the flues 20 into the chimney flues 22, from which they escape into the atmosphere. At the same time the gases from the fire boxes 26 pass through the flues 28 into the flues 29, and are then conducted through a suitable stack to the atmosphere.

It will be evident to those skilled in the

art that considerable change could be made in the detailed construction of the parts which I have described without departing from the spirit or scope of my invention.

5 What I claim is:

1. A kiln comprising a heating chamber, a plurality of heating flues forming an inner side of the chamber, the walls of adjacent flues being separated from each other throughout substantially the widths of the flues, and the spaces between the flues being open to the heating chamber,

10 2. A kiln comprising a heating chamber, a plurality of heating flues extending across the chamber and forming the floor thereof, the walls of adjacent flues being separated from each other throughout substantially the vertical widths of the flues, and the spaces between the flues being open to the

20 heating chamber.

3. A kiln comprising a heating chamber, a firebox in one wall of the chamber, flues leading upwardly from the firebox, each flue extending through the adjacent wall, across

the top of the chamber to the opposite side 25 wall thereof, thence downwardly through said opposite wall to the floor, thence across the floor and back to said opposite wall, and finally upwardly through said opposite wall.

30 4. A kiln comprising a heating chamber, a firebox in one wall of the chamber, flues leading upwardly from the firebox, each flue extending through the adjacent wall, across the top of the chamber to the opposite side 35 wall thereof, thence downwardly through said opposite wall to the floor, thence across the floor and back to said opposite wall, and finally upwardly through said opposite wall, the walls of adjacent flues being separated 40 from each other throughout substantially the widths of the flues, and the spaces between the flues being open to the heating chamber.

ENOCH P. STEVENS.
